UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 12, 1924. Serial No. 698,635.

To all whom it may concern:

Be it known that I, WALTER P. ALBERT, a citizen of the United States of America, residing at East Orange, in the county of 5 Essex and State of New Jersey, have invented certain new and useful Improvements in Telephone-Exchange Systems, of which the following is a full, clear, concise, and exact description.

10 This invention relates to telephone exchange systems and more especially to such systems as make use of automatic switches in the establishing and extending of connections.

15 The object of the invention is an improved means for registering the designations and testing the condition of called lines.

20 A feature of the invention resides in the manner in which a calling line is identified by a finder switch during its process of hunting therefor.

25 A further feature of the invention relates to the use of a register switch for controlling the operation of a connector switch, the latter being independent of the sleeve conductors of the called lines.

30 A further feature of the invention is the use of a register mechanism for controlling the operation of a connector switch, and for maintaining a seized called line non-selectable by other connector switches.

35 Another feature of the invention relates to a connector switch which hunts for a marked group of lines and then hunts for a particular one of a plurality of individually marked lines, this particular line being determined by the previously marked group.

40 Other features and advantages will be apparent after a consideration of the following detailed description and the appended claims.

45 The figures of the drawing when arranged in the manner shown in Fig. 5 disclose a preferred means for carrying out the invention.

50 Fig. 1 discloses a number of subscribers' lines and one of a plurality of central office trunks with associated controlling mechanism. In addition there is shown an automatic switch for connecting subscribers' lines to the trunks. This figure also shows an attendant's line circuit by means of which incoming calls may be extended to local stations.

55 Fig. 2 shows in addition to a number of

subscribers' lines, a finder switch and a connector switch. This figure also shows one of a number of link circuits with certain controlling apparatus for interconnecting local subscribers' lines.

60 Fig. 3 illustrates a register switch and a register relay mechanism associated with a central office trunk.

65 Fig. 4 illustrates a register switch and recording mechanism associated with a link circuit, and similar to the register mechanism of Fig. 3.

General description.

70 The finder switches 100, 200 and connector switch 260 are all of the same type, each switch consisting of a plurality of banks of terminals and cooperating wipers. These wipers are further divided in two sets which are positioned 180° apart. Thus, while one set of wipers is making contact with bank terminals, the other set is not. By means of this arrangement, the 22-point rotary switches each consisting of six banks and a common rotary shaft, may be used, the 80 number of contacts in each bank of which may be one-half the total number of subscribers' lines. The talking and test conductors of each line have an appearance in different banks of contacts of the finder switches 100 and 200. Thus the tip, ring and sleeve conductors of the first group of lines are terminated in the first of three banks of contacts while conductors of the second group of lines are terminated in the 85 second three banks. The sleeve conductors are also multiplied through contacts of cut-off relays to appear in contacts of the register relays shown in Figs. 3 and 4.

90 When one local subscriber desires to converse with another local subscriber, the removal of the receiver causes the finder switch 100 to hunt for and connect the calling line with an idle link circuit. The transmission of the tens series of impulses positions the 100 brushes of register switch 400 on the proper set of tens terminals and the corresponding register relay is operated. During the comparatively long period following the transmission of the tens impulses the brushes of switch 400 are automatically advanced to the next resting position. In the drawing this is shown as the No. 5 set of terminals. The calling subscriber upon dialing the units digit causes the brushes of the register 105

110

switch to be advanced to the proper set of units contacts. The test or sleeve conductor of the called line is now connected through a right front contact of the operated register relay, units contact and brush 427 of switch 400 to the winding of test relay 219 which operates if the called line is busy, causing busy tone to be transmitted back to the calling subscriber. Should, however, the called line be idle the connector switch 260 is operated, to hunt for the set of terminals marked by register switch 400.

The called lines, it will be observed, are arranged in groups, each group being provided with an identifying contact in the banks 263 and 264. In accordance with the operation of a particular one of the register relays shown in Fig. 4 the proper group contact is marked and when this contact is reached, relay 223 operates thus bringing the brushes of switch 260 to rest. After a short interval, the switch 260 is again operated to hunt for the particular units contact in the selected group, this units contact having been marked by means of ground extended over conductor 251 to brush 420 and thence to the particular units terminal in banks 263 and 264. When the brushes of switch 260 reach the terminals corresponding to the called line, relay 223 again operates and brings switch 260 to rest. Connecting relay 226 now operates to connect the calling and called lines.

When a local subscriber desires to converse with a subscriber reached by means of the central office the number 11 is dialed. The operation is similar to that already described as far as the point where register switch 400 is positioned. The setting of switch 400 in this case, causes the operation of relay 228, thus releasing the link circuit and operating a starting relay associated with the first idle outgoing trunk. A circuit is then completed for operating finder switch 100, the calling line previously having been marked by battery connected through the right front contact of cut-off relay 202. A test relay 104 is now connected in series with the winding of the cut-off relay but does not receive sufficient current to energize. However, when the terminals of the calling line are reached, battery is connected through the back contact of relay 108 in parallel with the winding of cut-off relay, thus providing sufficient current to operate relay 104. The brushes of switch 100 are now brought to rest upon the terminals of the calling line. Subsequently relay 105 operates thus completing connection of the calling subscriber's line with the central office trunk. The calling subscriber may now proceed to give verbally the number of the desired line in the case of a manual office or to dial the same in the case of a mechanical office.

On calls incoming from the central office the attendant is signaled by means of the lighting of lamp 140. The attendant answers by operating key 170 and receives the number of the desired station from the central office operator. Immediately thereafter a key 160 is operated and the number of the wanted station is dialed over the attendant's line circuit 190. The transmission of the tens and units impulses causes the brushes of switch 300 to be set in a manner similar to that described in connection with register switch 400, the proper one of the register relays shown in Fig. 3 being operated. As soon as the attendant commences dialing, switch 100 is operated to find the calling line which is marked by means of a units contact of switch 300 and a front contact of the operated register relay. When the terminals corresponding to the called line are reached, relay 104 operates in the same manner as described in connection with an outgoing call, thus bringing the brushes of switch 100 to rest.

Detailed description of a local call.

When a calling subscriber, as the subscriber at station 101, desires to talk with another local subscriber, removal of the receiver from the switchhook causes the line relay 201 to operate from battery through its right hand winding, left inner contacts of cut-off relay 202, ring side of the calling line, through the subscriber's substation apparatus back over the tip side of the line, left outer contacts of relay 202 to ground through the left winding of relay 201. Relay 201 at its right inner armature connects battery through resistance 203 in parallel with the winding of relay 202 to the sleeve conductor of the calling line, thus raising the potential of a particular one of the set of contacts with which brush 210 cooperates.

Relay 201 also connects ground through its outer armature and contact to the starting wire 206 and thence through the outer armature and back contact of relay 204, to battery through the winding of starting relay 205. Relay 205 locks in a circuit traceable from battery through its winding, armature and locking contact thereof, outer armature and contact of relay 212 to ground at the inner armature and contact of relay 204. If the particular link shown in Fig. 2 had been busy, relay 204, individual thereto, would be in operated condition and the starting wire 206 would be extended through the outer front contact of relay 204 to operate the starting relay associated with the next idle link. When relay 205 closes its left outer armature it connects ground through the armature and back contact of test relay 207, outer armature and contact of relay 208, interrupter contacts and winding of stepping magnet 209 to battery. Stepping mag-

net 209 is energized in an interrupted manner in this circuit and steps the brushes of the line finder switch 200 until the set of terminals is located in which the calling line terminates. When this particular set of terminals is reached, a circuit is completed from battery, through the winding of relay 202 and the resistance 203 in parallel, brush 210 and cooperating contact, winding of relay 207 to ground at the armature of relay 205. Relay 207 operates in this circuit and breaks the energizing circuit of stepping magnet 209, thus causing the brushes of switch 200 to come to rest on the set of terminals in which the calling line terminates, but relay 202 which is marginal, does not operate in this circuit. Relay 207 also extends the above traced ground through its armature and front contact, to battery through the winding of relay 208, which locks in a circuit from battery through its winding, armature and locking contact, left outer armature and contact of relay 228 to the grounded conductor 254. The operation of relay 208 connects the calling line to the windings of the impulse relay 211 which operates. At this time ground is extended through the left middle armature and contact of relay 208, conductor 255, brush 210, to battery through the winding of cut-off relay 202 which now operates and renders the calling line busy. The operation of relay 202 also causes the release of the line relay 201.

It will be observed that had the brushes of switch 200 been at rest on a set of terminals in advance of the set corresponding to the calling line, the brushes of switch 200 would necessarily have been rotated through almost a complete revolution before relay 202 operates to complete the dialing circuit. By means of relay 212, however, this time interval may be rendered comparatively inappreciable. When brush 220 reaches the last one of the associated bank of terminals (terminal #22) relay 212 operates from battery through its winding, brush 220 and cooperating terminal #22 winding of test relay 207 to ground at the armature of relay 205. The operation of relay 207 closes the above traced circuit for operating relay 208 which in turn closes the impulsing circuit as before described. The further stepping of the switch 200 to the terminals of the calling line is accomplished as previously described. Thus by means of relay 212 the dialing circuit may be completed before the brushes of switch 200 have connected with the calling line.

When relay 211 operates subsequent to the operation of relay 208, an obvious energizing circuit is closed for the slow releasing relay 213 which in turn closes an obvious circuit for the holding relay 214. Relay 214 connects ground through its left outer armature and contact of magnet 401, brush 421 of register switch 400, conductor 452 to ground at the left outer armature and front contact of relay 216. When the No. 5 set of terminals is reached, the above traced circuit is opened and the brushes of register switch 400 come to rest.

The calling subscriber dials the units digit of the desired station. At the first opening of the line circuit, relay 215 and the magnet 401 energize as before described. As soon

70 operates and transfers the starting wire 206 to the next idle link. The locking circuit of the starting relay 205 was opened by the operation of relay 204, the former relay now releasing. However, a substitute holding circuit is provided for relay 208 extending from ground at the left inner armature and contact of relay 214, conductor 254, left outer armature and contact of relay 228, armature and locking contact and winding of relay 208 to battery.

75 The calling subscriber now dials the tens digit of the wanted station. Relay 211 follows the impulses in the well known manner. Assume that the number of the desired station is 35. When relay 211 releases as a result of the first opening of the line circuit ground is connected through its armature and back contact, right outer armature and contact of relay 214, winding of relay 215, conductor 250, to battery through the winding of stepping magnet 401. When stepping magnet 401 releases as a result of the reoperation of relay 211, the brushes of register switch 400 are advanced to the No. 1 set 80 of terminals. In a similar manner the transmission of the second and third impulses of the tens series, advances the brushes of register switch 400 to the No. 3 set of terminals. At the termination of the comparatively long period following the transmission of the tens digit, slow relay 215 releases and closes a circuit from ground at the right inner armature and contact of relay 214, right normal contacts of relay 215, 85 left outer armature and back contact of relay 218, conductor 251, brush 420 and terminal No. 3 of register switch 400, conductor 451, winding of register relay 402, to battery. Relay 402 operates and extends 90 this same ground through its armature and locking contact, conductor 450, to battery through the winding of relay 216 which locks to ground at the armature and contact of relay 213. With relay 216 operated, a 95 circuit is completed for stepping magnet 401 to advance the brushes of switch 400 to the next resting position. In the case illustrated, this resting position would be the No. 5 set of terminals. The circuit for this 100 purpose may be traced as follows: battery, through the winding of stepping magnet 401, conductor 250, left inner armature and front contact of relay 216, conductor 256, armature and contact of magnet 401, brush 421 of register switch 400, conductor 452 to ground 105 at the left outer armature and front contact of relay 216. When the No. 5 set of terminals is reached, the above traced circuit 110 is opened and the brushes of register switch 400 come to rest.

115 The calling subscriber dials the units digit of the desired station. At the first opening of the line circuit, relay 215 and the magnet 401 energize as before described. As soon

as relay 215 operates, ground is extended through its right armature and front contact, right outer armature and contact of relay 216, to battery through the winding of line test relay 217. Relay 217 operates and closes an obvious energizing circuit for relay 218. At this time ground is extended through the right inner armature and contact of relay 214, middle armature and contact of relay 217, through the right hand winding of relay 225 to battery. Relay 225 locks in a circuit from battery through its left winding armature and locking contact thereof, right armature and contact of relay 222, right armature and back contact of relay 219 to ground at the armature of relay 214. Since the units digit of the called line is assumed to be 5, the line circuit is opened a corresponding number of times and register switch 400 will have its brushes positioned upon the No. 5 set of units terminals.

At the termination of the units dialing, relay 215 and magnet 401 release. The release of relay 215 opens the original energizing circuit of test relay 217. Before relay 217 retracts its armatures and assuming that the called line is busy, a circuit is closed from battery through the left winding of relay 219, inner armature and front contact of relay 217, left normal contacts of relay 215, conductor 252, brush 427 of register switch 400, conductor 458, right hand contact No. 5 of register relay 402 to the grounded sleeve conductor of the busy line. It should be observed that all the right hand contacts of the register relays shown in Figs. 4 and 5 are connected, by means of multiplies, through the right front contacts of cut-off relays, to the sleeve conductors of the different lines. Thus, the sleeve conductors of the first group of lines are multiplied to the right front contacts of register relays 305 and 405. In a similar manner, the sleeve conductors of lines in other groups are multiplied to appear in right contacts of the corresponding register relays. When relay 219 operates in the above traced circuit it also locks through its right-hand winding, right armature and locking contact, to ground at the right inner armature and contact of relay 214. A distinctive tone is thereupon transmitted to the calling subscriber from the tone source 257, left outer armature and front contact of relay 219, condenser 229, ring side of the line and thence to the calling subscriber, notifying him of the busy condition of the wanted line.

Should, however, the called line be idle when relay 215 releases the second time, there being no ground potential on the sleeve conductor of the called line, relay 219 will remain normal and thus allow test relay 217 to release. The release of relay 217 opens the original energizing circuit of relay 218

which does not release, however, since it is now locked in a circuit traceable from ground at the right inner armature and contact of relay 214, right normal contacts of relay 215, outer armature and front contact of relay 218, left outer armature and back contact of relay 221 to battery through the winding of relay 218. After a short interval when relay 217 releases, it connects ground through its inner armature and back contact, through the left normal contacts of relay 215, conductor 252, brush 427 of register switch 400 and thence through the contact of relay 402 to the sleeve of the called line, rendering this line busy to other calling stations. Should the connector switch 260 when relay 217 releases be resting upon a set of terminals not in the group assigned to lines having a tens digit of 3, a circuit is closed from battery through the winding of stepping magnet 222, armature and contact thereof, armature and back contact of relay 223, inner armature and front contact of relay 218 to ground at armature of relay 217. Stepping magnet 222 continues to operate in this circuit until the set of group terminals allotted to called lines having a tens digit of 3 is reached. When this set of group terminals is reached, relay 223 operates in a circuit traced from battery through its winding, brush 234 of connector switch 260, third group identifying terminal thereof, conductor 253, left outer armature and front contact of register relay 402, conductor 453, to ground at the right outer armature and back contact of relay 224. Relay 223 attracts its armature and breaks the operating circuit for magnet 222, thus causing brush 234 of switch 260 to come to rest on the marked group terminal. At the same time a circuit is completed from battery through the winding of relay 224, right armature and back contact of relay 221, armature and front contact of relay 223, inner armature and front contact of relay 218 to ground at the outer armature and back contact of relay 217. The operation of relay 224 causes the release of relay 223. When relay 223 releases, relay 224 locks in series with the winding of relay 221 which operates. When relay 224 operates a circuit for operating stepping magnet 222 similar to that above traced is completed, ground being supplied through the inner front contact of relay 224. This same ground is extended through the outer armature and front contact relay 224, conductor 251, brush 420 and units contact No. 5 of register switch 400, conductor 459 thence to units terminal No. 5 in group No. 3 of bank 284. This serves to mark this particular units terminal. Stepping magnet 222 continues to operate in the above traced circuit until the particular set of terminals is reached, which has been previously marked by means of reg-

ister switch 400. When this set of terminals is reached, relay 223 operates in turn bringing the brushes of switches 260 to rest.

- When relay 221 operates in series with the 5 winding of relay 224 the locking circuit for relay 218 is broken and this relay releases. A circuit is now completed for the relay 226 traceable from battery through its winding, right armature and front contact of relay 10 221, armature and front contact of relay 223 to ground at the right inner armature and front contact of relay 224. Relay 226 operates in this circuit and immediately 15 closes a locking circuit for itself from battery through its armature and locking contact to ground at the right inner armature and contact of relay 214. Relay 226 in operating causes the successive release of relays 224, 221 and 223.
- When relay 226 operates, the calling subscriber's line is extended by means of the 20 link circuit to the called subscriber's line. Ringing current is supplied from the source 261, winding of relay 232, right inner armature and front contact of relay 225, ring side of the link, right inner armature and front contact of relay 226, brush 231 and cooperating contact, thence over the ring side of 25 the called line and through the subscriber's ringing apparatus back over the tip side of the calling line, brush 230 and cooperating contact, right outer armature and front contact of relay 226 to ground at the right outer armature and front contact of relay 225.
- When the called subscriber removes his receiver from the switchhook the resistance of 30 the circuit above traced in series with the winding of relay 232 is reduced and this latter relay now operates and at its armature and contact breaks the locking circuit for relay 225 which releases and disconnects 35 ringing current from the called line. Talking current is furnished the called subscriber through the windings of retardation 40 coil 233 which is bridged across the outgoing end of the link.
- It will be observed that when relay 218 45 released as a result of the operation of relay 221, ground was connected through the right outer contact of relay 217, left inner armature and back contact of relay 218, left inner armature and front contact of relay 221, to battery through the winding of relay 270. Relay 270 attracts its armatures and connects ground to each of the group identifying contacts in terminal banks 263 and 264. The purpose of grounding these several contacts is to confine the units hunting operation of switch 260 to the particular group of contacts first selected. Thus, if for any reason brush 234 in its rotation fails to make contact with the marked units terminal, the brushes will be advanced to the next group identifying contact upon which ground is 55 found, thus causing relay 223 to operate and

prevent further hunting in the next group of contacts. This is necessary since all the units contacts are multiplied, the marking of one contact also marking a corresponding contact in each of the other groups; thus 70 failure to select the proper line in one group might result in the selecting of a corresponding line in another group.

Disconnection.

75

Following the conversation when the calling subscriber replaces his receiver upon the switchhook, relay 211 releases, in turn releasing relays 213, 214, 204, 208, 216, and 402. After a short interval when relay 213 80 closes its normal contacts, ground is extended over conductor 258, brush 421 of register switch 400, armature and contact of stepping contact 401, conductor 256, left inner armature and back contact of relay 216, winding of relay 215, conductor 250, back through the winding of stepping magnet 401. Magnet 401 continues to rotate the brushes of register switch 400 until the normal position is reached at which time the 85 above traced circuit is broken and switch 400 comes to rest.

All the relays associated with the link are now in normal condition thus rendering the 90 link selectable in connection with another 95 local call.

Outgoing central office calls.

When a local subscriber desires connection with the central office, a special code 100 is dialed. In the case illustrated this is 11. The sequence of operations when this number is dialed is similar to that for a local call. In this case, however, register switch 400 will have its brushes positioned upon the 105 No. 1 set of units terminals and register relay 405 will be operated.

When, therefore, relay 215 releases at the 110 termination of the dialing of the units digit, a circuit is completed from battery at the outer armature of relay 227 through the right hand winding of relay 228, conductor 259, right hand contact No. 1 of relay 405, brush 427 and cooperating contact, conductor 252, left normal contacts of relay 215 115 to ground at the inner armature and back contact of relay 217. Relay 228 operates in the above traced circuit and locks through its left winding, left armature and back contact of relay 102 to ground at the right outer armature and back contact of relay 108. At the same time relay 228 closes an obvious operating circuit for common relay 227 which operates thus preventing more than one calling subscriber being simultaneously connected with an outgoing trunk.

When relay 228 opens its left outer armature and back contact the locking circuit of relay 208 is broken and this latter relay now 120 releases. The release of relay 208 causes the 125

130

successive release of relays 211, 213, 214, 216, and the restoration of the register switch 400 to its normal position as already described under Disconnection. The link however, is not completely released since relay 204 is held operated by ground at the left middle armature and contact of relay 228. When relay 228 closes its right inner armature and contact it connects ground to the winding of relay 103 which operates. The operation of relay 103 connects ground to the ring side of the trunk serving as a signal to the central office. At the same time ground is extended through the left outer armature and contact of relay 103, left armature and back contact of relay 104, left armature and back contact of relay 105, armature and contact of magnet 106 to battery through the winding of the same. Magnet 106 steps the brushes of the finder switch 100 until the set of terminals corresponding to the calling line is reached, whereupon a circuit is completed from battery through resistance 107, left armature and back contact of relay 108, brush 110, and cooperating contact of switch 100, sleeve conductor of the calling line and thence in parallel with battery through the winding of relay 202, brush 210 and cooperating contact, right outer armature and contact of relay 228, right normal contacts of relay 102 to ground through the winding of relay 104. Relay 104 receives sufficient current in this circuit to cause its energization, resulting in the release of stepping magnet 106. The operation of relay 104 closes a circuit from battery through the winding of relay 105, right normal contacts of relay 108, armature and front contact of relay 104, to ground at the left outer armature and contact of relay 103. The operation of relay 105 connects the called line through the normal contacts of relay 113 with the winding of relay 111 which operates. Relay 111 at its left armature provides a substitute holding ground for relay 103. At its right armature relay 111 closes an obvious operating circuit for slow release relay 112. With relays 111 and 112 operated an energizing circuit is completed for relay 113 which locks in a circuit traceable from ground at the left outer contacts of key 160, right armature and contact of relay 112, armature and locking contact of relay 113 to battery. When relay 112 attracts its armatures, a circuit is also completed from battery through the winding of relay 108, left armature and contact of relay 112, right normal contacts of relay 117, to ground at the left outer contacts of key 160. Relay 108 operates and connects ground through its left armature and contact, brush 110 and cooperating contact, to the sleeve conductor of the calling line to render it busy to other calling subscribers. Relay 108 connects ground through its right outer armature and

front contact to the winding of relay 102 which operates and renders the selected trunk busy to other calling stations. When relay 102 operates it breaks the original locking circuit for relay 228 which releases, in turn releasing relay 227 to thereupon allow the association of other calling lines with central office trunks.

The calling line is now connected through the contacts of relays 105 and 113 with the central office trunk and the calling subscriber may proceed to dial the number of the desired line in the case of an automatic office or give the number verbally in the case of a manual office. When the connection of the calling line with the central office has been completed, supervisory relay 114 operates in a well known manner from a source of battery and ground at the central office. Relay 114 closes an obvious circuit for relay 115 which in turn closes the circuit of relay 116. Relay 116 at its left armature provides a substitute holding ground for relay 112.

When the calling subscriber disconnects, relays 114, 115 and 116 release in succession, causing the supervisory relay at the central office to release, as a disconnect signal. The release of the trunk is now under control of the central office since relay 120 is bridged across the trunk through the outer back contact of relay 116. Relay 120 at its armature provides a holding circuit for relay 112. However, when disconnection takes place at the central office, relay 120 releases causing the release of the trunk circuit and all the operated relays associated therewith.

Incoming calls.

When the central office trunk is connected to, either manually or as the result of seizure by a connector switch, relay 120 operates through both windings in series, since it is bridged across the trunk through a back contact of relay 116 and a normal contact of key 161. Relay 120 in energizing, closes an obvious operating circuit for slow-release relay 112. Relay 112 completes a circuit from battery through the right hand winding of relay 129, right armature and contact of relay 128, right armature and contact of relay 112, to ground at key 160. Relay 129 operates in this circuit and completes a locking path through its left hand winding, left armature and locking contact, right armature and contact of relay 163, right inner armature and back contact of relay 131, right armature and contact of relay 112 to ground at key 160. When ringing current is applied to the trunk, relay 118 operates through its left winding in series with the condenser 119. Relay 118 closes a locking circuit for itself from battery through its right hand winding, right armature and locking contact, left inner armature and back contact of relay 121,

left normal contacts of relay 122, right armature and contact of relay 112, to ground at key 160. This last traced ground is also extended through the left armature and contact of relay 118, causing line lamp 140 to be illuminated as a signal to the attendant. The attendant answers by operating key 170 which causes the talking set 180 to be connected through the normal contacts 10 of relay 123 with the outgoing end of the central office trunk. The operation of key 170 also completes an obvious operating circuit for relay 121 which locks in a circuit from battery, through its winding, left inner armature and locking contact to the previously traced ground at key 160. The operation of relay 121 causes line lamp 140 to be extinguished and retardation coil 127 to be connected in parallel with the right hand high resistance winding of relay 120.

Having learned the number of the wanted station the attendant operates key 160 causing relay 123 to attract its armatures. When relay 123 operates, the attendant's line circuit 190 is disconnected from the outgoing end of the trunk and is transferred to the local end thereof, resulting in the operation of relay 111 through the normal contacts of relay 113. Relay 111 at its left armature 30 connects ground through the left inner armature and back contact of relay 103 to battery through the winding of relay 124 which operates. Relay 124 completes an obvious operating circuit for relay 117. Relay 117 at its left inner armature connects ground through the winding of relay 125 to battery at the armature of relay 227. Relay 125 operates and completes an obvious energizing circuit for relay 227 thus preventing simultaneous seizures of this central office trunk. Relay 125 also locks from battery through its right winding, right armature and locking contact, right outer armature and contact of relay 117 to ground at the right outer armature and back contact of relay 108. At this time relay 102 operates to render the central office trunk busy. The circuit for this purpose may be traced from battery through the winding of relay 102, right inner armature and front contact of relay 117 to ground at key 160.

The attendant now dials the number of the desired station, relay 111 following the impulses in the well known manner. At each opening of the line circuit, relay 111 releases and connects ground through its left armature and back contact, left armature and contact of relay 124, winding of slow-to-release relay 126, conductor 152 to battery through the winding of stepping magnet 310. Relay 126 operates and the magnet 310 is seized. Assuming the number of the called line to be 36, then magnet 310 will receive three current impulses thus

causing the brushes of register switch 300 to be advanced to the No. 3 set of terminals. At the end of the tens dialing period, relay 126 releases and completes a circuit from battery through the winding of register relay 302, brush 320 and cooperating contact, conductor 351, right normal contacts of relay 126, to ground at the left outer armature and contact of relay 117. This same ground is extended through the left armature and locking contact of relay 302 to cause the operation of relay 130 which also locks. The operation of relay 302 connects the sleeve conductors of the group of lines having a tens digit of 3 with the set of units contacts in switch 300.

When relay 126 releases at the end of the first dialing period a circuit is completed for advancing the brushes of switch 300 to the next resting position upon the No. 5 set of terminals. This circuit may be traced from ground at the right normal contact of relay 124, conductor 153, brush 330 and cooperating contact, armature and contact of magnet 310, conductor 350, left inner armature and front contact of relay 130, conductor 152 to battery through the winding of stepping magnet 310. When the No. 5 set of terminals is reached the above traced circuit is broken and the brushes of switch 300 come to rest.

The attendant upon transmitting the units set of impulses causes relay 126 to become energized and the stepping magnet 310 to alternately operate and release until the proper set of units terminals is reached. At the completion of the units dialing relay 126 and stepping magnet 310 release. A test is now made of the called line in the following manner. Relay 128 which operated when relay 130 was energized now completes a circuit from battery, through the left winding of relay 131, left armature and front contact of relay 128, left normal contact of relay 126, conductor 154, brush 353 and cooperating contact, right hand contact No. 6 of relay 302 to the sleeve conductor of the called line. Should the called line be busy a ground potential will be found on the sleeve conductor and relay 131 will operate in the last traced circuit thus providing at its right outer armature and contact a holding circuit for relay 128. A distinctive tone will now be transmitted from the tone source 155, left armature and contact of relay 131, ring side of the trunk, thence through contacts of relay 123 and key 170, through the attendant's set. The attendant thereupon releases key 160 thus replacing the talking set 180 in communication with the central office by the release of relay 123 and she may now proceed to notify the central office operator of the busy condition on the called station.

Should however the called station be idle,

when relay 126 releases the second time, there will be no ground potential on the sleeve conductor of the called line, thus permitting relay 131 to remain normal and the 5 subsequent release of relay 128.

When relay 125 operated subsequent to the operation of keys 160 and 170 a circuit was completed from battery, through the winding of stepping magnet 106, armature and 10 contact thereof, left armature and contact of relay 105, left armature and back contact of relay 104 to ground at the armature and contact of relay 125. Magnet 106 continues to advance the brushes of switch 100 15 by means of this self-interrupting circuit. When however, register switch 300 has been set, ground is connected through the winding of low resistance identifying relay 104, left armature and back contact of relay 128, left 20 normal contacts of relay 126, conductor 154, brush 353 and No. 6 units terminal, right hand contact No. 6 of relay 302, sleeve conductor of the called line to battery through the winding of cutoff relay 202 which operates, but relay 104 does not. Battery is 25 now connected through the winding of relay 202, right armature and contact thereof, conductor 262, to a contact in the terminal bank with which brush 110 cooperates. 30 When brush 110 during its rotation reaches this particular terminal, battery is connected through resistance 107, left armature and back contact of relay 108, brush 110 and thence in parallel with battery through the 35 winding of relay 202, to ground through the identifying relay 104 as above traced. Relay 104 receives sufficient current in this circuit to energize thus causing the brushes of switch 100 to come to rest upon the terminals of the called line. Relay 105 now 40 operates from battery through its winding, right normal contacts of relay 108, left armature and front contact of relay 104 to ground at the armature of relay 125. Ringing current is now supplied to the called line from the ringing source 162, winding of relay 163, right inner armature and front contact of relay 129, ring side of the trunk, thence to the ring side of the called line 45 through the called subscriber's apparatus back over the tip side of the called line and thence over the tip side of the trunk to ground at the right outer armature and contact of relay 129. 50 The attendant may now release keys 160 and 170. The release of key 170 disconnects the talking set from the trunk causing the successive release of relays 111, 124, 117, 125, 130, 302 and 104. A circuit is now closed 55 from battery through the winding of relay 108, left armature and contact of relay 112, right normal contact of relay 117, to ground at key 160. The operation of relay 108 connects ground through its left armature and front contact, brush 110 and cooperat-

ing contact to the sleeve of the called line rendering it busy to other calling stations and maintaining relay 202 energized. Relay 108 also provides at its right outer armature and front contact a holding circuit 70 for relay 102, to replace the previously traced holding circuit through the contact of relay 117. At its right inner armature and front contact relay 108 provides a substitute holding circuit for relay 105. 75

Register switch 300 is now restored to its normal position. This circuit may be traced from battery through the winding of stepping magnet 310, conductor 152, winding of relay 126, left inner armature and 80 back contact of relay 130, conductor 359, armature and contact of magnet 310, brush 330 and cooperating contacts, conductor 354, left outer armature and back contact of relay 130, to ground at the right normal contacts 85 of relay 124. Guard lamp 164 is now lighted from ground at key 160, right armature and contact of relay 112, right outer contact of key 170, right inner armature and back contact of relay 122, right outer armature and 90 contact of relay 121, to battery through the lamp 164. Guard lamp 164 remains lighted until the called subscriber answers.

When the called subscriber removes the receiver from the switchhook, relay 163 95 operates thus causing the release of relay 129 and the disconnection of ringing current from the called line. Relay 111 now operates through the normal contacts of relay 113, whereupon a circuit is closed from 100 ground at the left armature and front contact of relay 111, right inner contacts of key 160 to battery through the winding of relay 113. Relay 113 immediately locks in a circuit extending through the right armature and contact of relay 112 to the above 105 traced ground, thus causing the release of relay 111. The called line is now connected directly with the central office trunk causing supervisory relay 114 to operate. Relay 114 110 causes the successive energization of relay 115 and 116. Relay 116 in operating causes the release of relay 120. However, relay 112 is maintained energized by ground at the left armature and contact of relay 116. 115 The release of relay 111 connects ground through its right armature and back contact, right outer armature and front contact of relay 113, left outer armature and contact of relay 121 to battery from the winding of relay 122 which locks in a circuit 120 traceable from battery through its winding, armature and locking contact, right outer contacts of key 170, right outer armature and contact of relay 112 to ground at key 160. 125 The guard lamp is extinguished as a result of the operation of relay 122.

When the called subscriber replaces his receiver, relay 114 releases, in turn releasing relays 115 and 116. The release of re- 130

mainder of the connection is under the control of the central office since relay 120 re-operates when relay 116 releases. This provides a holding circuit for relay 112. When ⁶ disconnection takes place at the central office, relay 120 releases causing the release of the remainder of the connection.

The local subscriber may recall the attendant by depressing the switchhook momentarily thus causing relays 114, 115 and 116 to reoperate. A circuit is now completed from battery through line lamp 140, right outer armature and contact of relay 122, left inner armature and back contact ¹⁰ of relay 121, left armature and front contact of relay 122 to ground at the armature of relay 116. Lamp 140 is illuminated in this circuit and serves as a recall signal to the attendant, who answers by operating ¹⁵ keys 160 and 170.

The attendant may signal the central office operator by operating and releasing key 156, causing the release of supervisory relay in the central office. The trunk supervisory relay 114 however, remains energized in series with attendant's set 180 and resistance 157.

By means of key 161 the attendant may originate a call to the central office and later ³⁰ extend this same call to any station as previously described.

What is claimed is:

1. In a telephone system, calling lines, central office trunks, a plurality of automatic switches each individual to a trunk and common to a number of calling lines, a cut-off relay for each of said calling lines, a test relay for each of said trunks, means for energizing a cut-off relay prior to the ³⁵ operation of one of said automatic switches, a circuit for the corresponding test relay, means under control of said cut-off relay for partially completing said circuit, and means rendered effective when said one of ⁴⁰ said automatic switches locates a calling line for completing the circuit of said test relay to thereby prevent further operation of said automatic switch.

2. In a telephone system, a calling line, ⁵⁰ a link circuit, a central office trunk, a cut-off relay for said calling line, a plurality of sets of line finder switches, one set of said finder switches adapted to connect the calling line with the link circuit, the other set of said finder switches adapted to connect the calling line with the central office trunk, means responsive to the initiation of a call to cause the first of said sets of line finders to seize and connect with the calling line, a test relay for said central office trunk, a test circuit extending through the winding of said cut-off relay, means rendered effective when a line finder of the first set has seized the calling line and responsive to the ⁵⁵ transmission of particular series of impulses

to cause a line finder of the second set to seize the calling line, means rendered effective when the calling line has been so seized for completing said test circuit through said cut-off relay and said test relay to prevent ⁷⁰ further operation of the line finder of the second set, and means rendered effective upon the operation of said test relay to complete the connection of the calling line with the central office trunk and to release the ⁷⁵ said first line finder.

3. In a telephone system, a calling line, a cut-off relay, a plurality of outgoing trunks, registering mechanism, an automatic switch for finding the calling line and associating the same with said register mechanism, means responsive to the transmission of a special code for causing the association of said calling line with an idle outgoing trunk, identifying means associated with ⁸⁰ said outgoing trunk, a second automatic switch, means effective upon the association of an idle outgoing trunk for causing said second automatic switch to operate to find the calling line, means under the control of said cut-off relay for marking the calling line, and means effective upon the finding of the calling line by the second automatic switch for causing, said cut-off relay and ⁸⁵ said identifying means to cooperate in bringing said second automatic switch to rest.

4. In a telephone system, called lines, a plurality of trunks, an operator's position, an impulse transmitting device at said position, registering means comprising relay and switch recording mechanism, means for setting said registering means in accordance with the impulses transmitted, means under control of said registering means for marking one of said called lines, an automatic switch, means effective upon the transmission of impulses for causing said automatic switch to hunt for the called line, a relay individual to the called line, a plurality of identifying means each individual to one of said trunks, and means effective upon the finding of the called line for causing said relay and one of said identifying means to cooperate in bringing said automatic switch ⁹⁰ to rest.

5. In a telephone system, telephone lines, a plurality of link circuits for interconnecting said lines, a switch common to a number of said lines and responsive to the initiation of a call on one of said lines for connecting said line to an idle one of said link circuits, a progressively movable switch operable in accordance with the busy or idle condition of another of said lines for connecting said one of said link circuits to the second mentioned line, and a register mechanism for recording the designation of said second mentioned line and for allowing a test to be made thereof prior to the operation of said progressively movable switch.

6. In a telephone system, a plurality of calling lines, a plurality of called lines, a plurality of link circuits, for extending said calling lines, a progressively movable switch common to a number of called lines for connecting an extended calling line to a particular one of said called lines, testing means, a circuit for said means, and a recording mechanism operable in accordance with a portion of the designation of a called line for completing the circuit of said testing means prior to the operation of said progressively movable switch.
7. In a telephone system, a calling line, a called line, a plurality of link circuits, means effective upon the initiation of a call for extending said calling line to an idle one of said link circuits, a progressively movable switch individual to said one of said link circuits for connecting said calling line to said called line, register means comprising switch and relay recording mechanisms, testing means, and means rendered effective upon the operation of said register means for connecting said testing means to the test conductor of the called line prior to the operation of said progressively movable switch.
8. In a telephone system, calling and called lines, a plurality of automatic switches each common to a number of calling lines, a plurality of link circuits each individual to an automatic switch, a test conductor for each calling and called line, a group of relays operable in accordance with a portion of the called line numerical designation, contacts in said group of relays in which the test conductors of called lines terminate, and a progressively movable switch common to a number of called lines and controlled by certain of said relays and the condition of the associated test conductors.
9. In a telephone system, a calling line, a called line, a connecting circuit for extending said calling line to said called line, a plurality of registers each individual to a connecting circuit, a plurality of connector switches, means controlled by one of said registers for testing said called line and causing the operation of one of said connector switches, and means independent of said connector switch and controlled by said register for maintaining said called line non-selectable by other connector switches.
10. In a telephone system, a calling line, a plurality of called lines arranged in groups, link circuits for extending said calling line to any one of said called lines, a register mechanism, connector switches, means controlled by said register mechanism and one of said connector switches for mark-

ing line groups and individual lines, and means controlled by said register mechanism and independently of said connector switch for maintaining an individual called line non-selectable by other connector switches.

11. In a telephone system, a plurality of calling lines, a called line, a connecting circuit for extending one of said calling lines to said called line, a register for said connecting circuit and common to said plurality of calling lines, means controlled by said register for determining the busy or idle condition of said called line, a connector switch in which said called line appears, means under control of said register for operating said connector switch to seize the called line, and means controlled by the register for maintaining the called line busy independent of the setting of said connector switch.

12. In a telephone system, calling lines, called lines arranged in groups, link circuits for interconnecting said calling and called lines, switch and relay recording mechanisms, a connector switch, means controlled by said relay recording mechanism for marking the group in which a particular called line is located, means under joint control of said relay and switch recording mechanisms for causing said connector switch to hunt for the particular called line group, means controlled by said switch recording mechanism and subsequent to the finding of said called line group for marking other called lines in other groups, and means effective when said called line group has been so found for causing said connector switch to hunt for and seize the particular marked line in the selected group.

13. In a telephone system, calling lines, called lines arranged in groups, link circuits for interconnecting said calling and called lines, register means comprising relay and switch recording mechanisms, a connector switch, means controlled by said relay recording mechanism for marking the group in which a particular called line is located, means under control of said registering means for causing said connector switch to select said particular called line group, means effective when said group has been so selected for marking the remainder of said called line groups and a different called line in each group, and automatic means for continuing the operation of said connector to seize the individually marked line in the selector group and to prevent the selection of an individually marked line in another group.

In witness whereof, I hereunto subscribe my name this 4th day of March A. D., 1924.

WALTER P. ALBERT.
